COMBINED POCKET BRUSH AND SHOE HORN

Albert Abrams, Great Neck, N. Y., assignor to Knomark Manufacturing Co., Inc., Brooklyn, N. Y., a corporation of New York

Application October 7, 1957, Serial No. 47,998

Term of patent 14 years

(Cl. D9—2)

FIG. 1

FIG. 2 FIG. 3

FIG. 4

FIG. 5

FIG. 6

FIG. 7

Fig. 1 is a front elevational view of a combined pocket brush and shoe horn embodying my new design with the brush portion in fully extended position.

Figs. 2 and 3 are left and right side elevational views thereof.

Fig. 4 is a bottom plan view thereof.

Figs. 5 and 6 are rear and front views, respectively, of my combined pocket brush and shoe horn with the brush portion shown in fully retracted position, and

Fig. 7 is a top plan view thereof.

I claim:

The ornamental design for a combined pocket brush and shoe horn, as shown.
